JOHN C. KILGORE, OF PHILADELPHIA, PENNSYLVANIA.

Letters Patent No. 84,427, dated November 24, 1868.

IMPROVEMENT IN STEAM-GENERATORS.

The Schedule referred to in these Letters Patent and making part of the same.

To all whom it may concern:

Be it known that I, JOHN C. KILGORE, of Philadelphia, in the county of Philadelphia, and State of Pennsylvania, have invented a new and valuable Improvement in Steam-Boilers; and I do hereby declare that the following is a full, clear, and exact description of the construction and operation of the same, reference being had to the annexed drawings, making a part of this specification, and to the letters and figures of reference marked thereon.

Figure 1, of the drawings, is a representation of a top view of my steam-boiler;

Figures 2 and 3 are sectional views thereof; and Figure 4 is a detail.

My invention relates to that class of steam-boilers or generators in which the steam is principally formed in cylinders or tubes connected with a water-reservoir encircling the same; and the object is to secure a constant supply of water in the tubes, and thereby prevent explosions.

The invention consists mainly in constructing and adjusting a return-tube or siphon, of the form shown on the drawings, and hereinafter described, with one end resting near the bottom of the steam-tube, and the other resting near the bottom of the reservoir.

The letter A, of the drawings, represents the outside shell of the boiler.

Letter B is the water-reservoir or chamber, and Letters C are the steam-generating tubes.

Letter D is the fire-box, and

Letter E is the smoke-flue.

The water is supplied to the reservoir by a pipe leading into the same, near the bottom thereof.

The letter H is my return-tube or siphon. I prefer to construct it in the form shown on fig. 3, and extending from the bottom of the reservoir to the bottom of the generating-tube.

The lower ends of this siphon are respectively cut open, and turned outward, as shown on fig. 4, thereby

forming something analogous to legs setting on the bottom of the generator or reservoir, as the case may be, and affording ready access for the water to the interior thereof. In case either end of the siphon does not rest upon the bottom, the form of such end, as above described, may be dispensed with.

In some cases the siphon need not be extended downward into a water-chamber, such as the drawings represent, but in all cases it must be connected with a water-reservoir of some description, and lead from such chamber to a point near the bottom of the steam-generating tube. I always adjust one of these siphons in each generating-tube.

The letter e is a foam-cap, attached to the curved part of the siphon at the point, and in the manner and form shown on fig. 4, the office of which is to break the foam, and prevent the water from being drawn into the steam-pipe. This foam-cap not only serves to quiet the water to a great extent, but also serves to aid the operator in ascertaining the state of the water in the boiler.

The letter P is a plate, on the inside of the fire-chamber, immediately in front of the smoke-flue, arranged in such manner as to form a supplemental chamber.

In burning bituminous coal, this plate becomes intensely heated, and it serves not only as a means for detaining the gas in the fire-chamber, but also as an important auxiliary for the combustion of the same.

What I claim as my invention, and desire to secure by Letters Patent, is—

The foam-cap e, combined with the siphon H and tubes C, substantially as herein specified.

In testimony that I claim the above, I have hereunto subscribed my name in the presence of two witnesses.

J. C. KILGORE.
